Nicholas Müller's Design for a **CLOCK CASE**

4237

PATENTED JUL 19 1870

Johann Peter Heckersberg
Charles Fritschel

Nicholas Müller

United States Patent Office.

NICHOLAS MÜLLER, OF NEW YORK N. Y.

Design No. 4,237, dated July 19, 1870.

DESIGN FOR A CLOCK-CASE.

The Schedule referred to in these Letters Patent and making part of the same

To all whom it may concern:

Be it known that I, NICHOLAS MÜLLER, of the city, county, and State of New York, have invented a new and ornamental Design for a Clock-Case; and I do hereby declare that the following is a full, clear, and exact description thereof, which will enable those skilled in the art to make and use the same, reference being had to the accompanying photograph forming part of this specification, in which the design is represented by a front view.

This invention relates to a design for a clock-case.

For convenience in description, it may be divided into two parts by the line of division *ll*—

a a being the upper, and

b b the lower part.

The main feature of the design consists in a horse's bust, (head and neck,) fiery and spirited, resting on a suitable base, ornamented with leaves, which forms the part *a a* of the design, as may be seen in the photograph.

In the part *b b*, on each side, is an ornamental column, commencing near the bottom edge, which supports the top part *a a*.

Between the two columns, near the upper portion of the part *b b*, the dial is situated; above it is a medallion-head of a girl, forming part of the top edge.

Beneath the dial is a bear's head, protruding an arabesque.

The bottom portion of this part *b b* contains in the center an arabesque, on each side of it a medallion-head of a boy, and is shaped and ornamented, as seen in the photograph.

The whole background is embellished by twigs and branches of ivy leaves.

What I claim as my invention, and desire to secure by Letters Patent, is—

The parts *a a* and *b b*, separate and combined, of the design for a clock-case, as herein shown and described.

Signed this 17th day of May, 1870:

NICHOLAS MÜLLER.
